CLAIM

The ornamental design for a slotted ventilated post for a rear corner of a terrarium, as shown and described.

DESCRIPTION

FIG. 1 is a top, front perspective view of the slotted ventilated post for a front corner of a terrarium showing my new design;

FIG. 2 is a front elevational view thereof;

FIG. 3 is a right side elevational view thereof;

FIG. 4 is a rear elevational view thereof;

FIG. 5 is a left side elevational view thereof; and,
FIG. 6 is a top plan view thereof with the bottom plan view
being identical.
